UNITED STATES PATENT OFFICE.

LEO F. ADT, OF ALBANY, NEW YORK.

ADJUSTABLE NOSE-GUARD.

No. 887,904.

Specification of Letters Patent.

Patented May 19, 1908.

Application filed December 8, 1906. Serial No. 346,883.

To all whom it may concern:

Be it known that I, LEO F. ADT, of Albany, in the county of Albany and State of New York, have invented certain new and useful 5 Improvements in Adjustable Nose-Guards; and I do hereby declare the following to be a full, clear, and exact description of the same, reference being had to the accompanying drawings, forming a part of the specification, and to the reference-numerals marked 10 thereon.

My present invention relates to improvements in eyeglasses, and has for its object to provide improved nose guards therefor embodying a nose-engaging pad or surface which may be readily adjusted in order to insure a perfect fitting of the eyeglasses on the wearer's nose, the nose guard being so constructed that it may be easily punched and 20 formed from sheet material, insuring ample strength thereof and enabling the guards to be cheaply produced.

To these and other ends the invention consists of certain improvements and combinations of parts, all as will be hereinafter more fully explained, the novel features being pointed out in the claims at the end of the specification.

In the drawings: Figure 1 is a perspective 30 view of a portion of an eyeglass carrying a nose guard constructed in accordance with my present invention. Fig. 2 is a rear elevation of the guard shown in Fig. 1, the full and dotted lines indicating the forward and rear 35 adjustments of the upper pad or top. Fig. 3 is a rear perspective of another form of the invention, and Figs. 4 and 5 are perspectives of other forms of guards constructed in accordance with my present invention.

Similar reference numerals in the several 40 figures indicate similar parts.

The present invention provides a nose guard composed preferably of flat material and embodying a lower relatively rigid supporting pad, and an adjustable upper pad or surface connected to the body of the guard by a bend that will enable the pad to be easily adjusted, so as to properly fit the wearer's nose, and to obtain a hold on the fleshy portion that will serve to steady the eyeglasses and prevent slipping out of place.

The nose guard shown in Figs. 1 and 2 embodies an attaching portion 1 formed in the present instance to rest in the vertical opening in the ordinary stud or post, and having 55 a downwardly-extending portion forming a

relatively rigid or firm lower bearing surface 2 adapted to engage the bony or solid portion of the nose. The upper or adjustable nose-engaging portion in this form is supported on an arm 3 proceeding rearwardly edgewise of the material and from a point intermediate of the lower pad and the point of attachment of the guard, as this enables the guard to be applied to a stud or box having a vertical aperture or slot without this supporting arm interfering with the flange of the stud, and proceeding edgewise from the upper edge of this arm is a connecting portion which extends first downwardly in rear 70 of the supporting arm; thence inwardly past its lower edge and thence upwardly, forming a bend 4 which in the present instance is in the form of a coil, the upper pad 5 being carried on the free end thereof and arranged 75 above and in rear of the lower pad and adapted to engage the fleshy portion of the nose, the bend or coil supporting the upper pad enabling the latter to be tilted forwardly or rearwardly as shown in Fig. 2 to enable it to 80 engage the proper portion of the nose to obtain the requisite hold, relative inward and outward adjustment being also permitted by this adjustable connecting portion. This pad, if desired, may be perforated to permit 85 the edges of the metal to engage the skin or flesh and thus prevent slipping of the guard.

In Figs. 3, 4 and 5, the nose-engaging surfaces of the pads are connected by bends which proceed from the substantially vertical edges of the metal, the guard being attached to the stud or mounting by an arm 6 having a vertical attaching lug 7 thereon, the lower pad proceeding from the lower edge of the arm 6 and the arm 8 extending edge- 95 wise from the upper edge thereof, the arm 8 in the guard shown in Fig. 3 being bent first rearwardly; thence outwardly, forwardly, and thence inwardly to form a horizontal bend having the upper pad 9 attached thereto, this bend or adjustable connecting portion between the pads or nose-engaging portions in this form lying wholly in rear of the nose-engaging surface thereof and enabling the relation of the pads to be adjusted as 105 may be desired.

The nose-engaging portions or pads in Fig. 4 are connected by an arm 10 extending first upwardly edgewise of the material; thence rearwardly, then bending inwardly 110 flatwise of the material, finally extending upwardly and provided with an upper nose

pad 11, while the upper pad 12 in Fig. 5 is adjustably connected to the body of the guard by a loop or bend 14 formed similarly to the bend shown in Fig. 4 except that it is 5 bent rearwardly from the face of the lower pad.

The pads shown in Figs. 3, 4 and 5 may be readily adjusted forwardly or rearwardly by 10 means of pliers applied to the adjustable connecting loops or bends, and in each of the nose guards shown, the forward and rearward adjustment of the upper pads may be effected without altering the height of this 15 pad relatively to the lower pad, and it will remain in adjusted position so as to obtain the requisite hold on the proper portion of the nose.

I claim as my invention:

20 1. In eyeglasses, the combination with a lens, of a nose guard composed of flat material embodying a lower nose-engaging portion, and a supplemental or upper pad connected to the guard by a convolution formed 25 flatwise of the material the edges of which are arranged in planes substantially parallel to that of the lens.

2. A nose guard for eyeglasses composed of flat material embodying an attaching por-

tion, a lower nose-engaging portion, an arm 30 proceeding rearwardly from the edge of the guard at a point intermediate the nose-engaging and attaching portions, and an upper or supplemental nose pad connected to said arm by a bend flatwise of the material, ar- 35 ranged entirely below the nose bearing portion of the supplemental pad.

3. In eyeglasses, the combination with a lens, of a nose guard composed of flat material and embodying a lower bearing pad, 40 an attaching lug, an arm proceeding rearwardly from the edge of the guard at a point intermediate the lower pad and the attaching lug, and an upper or supplemental pad connected to said arm by a convolution pro- 45 ceeding from an edge thereof and bent flatwise of the material, the sides of the convolution lying in a plane substantially parallel to that of the lens.

4. A nose guard comprising a lower nose 50 engaging portion, an arm proceeding rearwardly from the guard, and an upper nose engaging portion connected to the arm by a convolution passing about the arm.

LEO F. ADT.
